UNITED STATES PATENT OFFICE

ALBERT K. HAET, OF ST. LOUIS, MISSOURI

FUSE PLUG AND SOCKET

Application filed December 30, 1929. Serial No. 417,486.

This invention appertains to new and useful improvements in fusible elements and sockets therefor, and more particularly to a fuse plug and socket which has as its principal object, the provision of means, whereby the liability of being shocked when mounting or demounting the plug is almost impossible.

Another important object of the invention is to provide improvements in fuse plugs and sockets, which while possessing considerably more merit over conventional types, does not increase the cost thereof.

These and numerous other important objects and advantages of the invention will become more apparent to the reader after considering the invention as described and claimed hereinafter.

In the drawings:—

Figure 1 represents a fragmentary section²⁰ al view through the socket constructed with the novel plug engaged therein.

Fig. 2 represents a top plan view of the plug.

Fig. 3 represents a fragmentary top plan²⁵ view of the panel with the plug removed.

Fig. 4 represents a bottom plan view of the conductor supporting strip.

Fig. 5 represents a sectional view through the fuse plug.

Fig. 6 represents a cross sectional view³⁰ thru the fuse socket panel, showing a fuse plug engaged therewith.

Fig. 7 represents a fragmentary bottom plan view in section, showing the legs of the³⁵ plugs in conductor engaged position.

Fig. 8 represents a fragmentary edge elevation of the socket panel with a fuse plug engaged therewith.

Referring to the drawings wherein like⁴⁰ numerals designate like parts, it can be seen that the fuse socket panel is constructed of a top strip 5, a bottom strip 6, and an intermediate or conductor supporting strip 7, each being of some suitable di-electric material.

Each socket construction consists in providing the top strip 5 with a circular opening 8 projecting inwardly into this opening 8 and in spaced relation with respect thereto, is the protuberance 9 on the bottom strip 6.

The intermediate strip 7 is provided with

an opening 10 concentric with respect to the cylindrical shaped protuberance 9.

The strip 5 is provided with a counter-bore 11 for receiving the body or shell portion 12 which is generally referred to by ⁵⁵ the numeral 13. The strip 5 at its diametrically opposite points of the opening 8 is provided with recesses 14.

As is clearly shown in Fig. 7, the strip 7 is provided with a pair of diametrically opposed projections 15 protruding into the opening 10, one of the same being offset toward one side of one of the recesses 14, while the other is offset in the opposite direction from the other recess 14, as in the manner ⁶⁰ clearly shown in Fig. 3.

Extending up from one of the projections 15 is the contact strip 16, secured by a suitable means 17 to the binding post or connector 18. The plug 13 includes the di-electric shell 12, aforementioned, which is flanged at its open end as at 19. A rim 20 engages over the flange 19 for supporting the transparent pane 21. A pair of legs 22—22⁷⁰ protrude from the closed end of the shell 75 and are connected at their inner ends by the fusible elements 23.

The outer free ends of the legs 22—22 are bent laterally in opposite directions as at 24. As is clearly apparent, these laterally bent ⁸⁰ portions 24 are adapted to be engaged through the recesses 14—14 for disposition in the opening 10. By rotating the plug, the portions 24 of the legs 22 may be swung from the position shown in Fig. 4 to the position ⁸⁵ shown in Fig. 7, thus contacting the legs 22 with the contact strip 16 and closing the circuit to be protected.

It can thus be seen that it is practically impossible to obtain a shock in manipulating ⁹⁰ the fuse plug to a circuit closed position. Furthermore, a socket panel constructed in accordance with the foregoing specification, can be manufactured much cheaper than the individual sockets now sold on the market. ⁹⁵

It will be noted in Figures 1, 2 and 6 that the rim 20 is provided with an ear 25 which will permit the sealing of the fuse in a position with the lateral extensions 24—24 disengaged from the contact members 16—16. ¹⁰⁰

The foregoing specification sets forth the invention in detail, yet it is to be understood that changes in the shape, size, materials, may be resorted to without departing from the spirit and scope of the invention as claimed hereinafter.

Having thus described my invention, what I claim as new is:—

In combination, a fuse plug, a socket structure, said socket structure comprising a top section, a bottom section, an intermediate section, said top section being provided with an opening therethrough, said intermediate section being provided with an opening of larger circumference, a protuberance extending from the bottom section through the aforementioned openings spaced from the walls of said openings, contact elements secured to the intermediate section and abutting parts of the outer side wall of said openings whereby said contact elements are located under parts of the top section, said plug being provided with laterally disposed contact legs for disposition in the opening of the intermediate section, for engaging the said contact elements, and stop projections extended inwardly from the side wall of the opening in the intermediate section and abutting ends of the contact elements and acting as stops to limit the movement of the said legs of the plug.

In testimony whereof I affix my signature.

ALBERT K. HART.
